UNITED STATES PATENT OFFICE.

SPENCER OTIS, OF CHICAGO, ILLINOIS, ASSIGNOR TO NATIONAL PATENT HOLDING COMPANY, OF SOUTH DAKOTA, OF RAPID CITY, SOUTH DAKOTA, AND CHICAGO, ILLINOIS, A CORPORATION OF SOUTH DAKOTA.

CAR-TRUCK.

SPECIFICATION forming part of Letters Patent No. 739,910, dated September 29, 1903.

Application filed March 19, 1902. Serial No. 98,908. (No model.)

To all whom it may concern:

Be it known that I, SPENCER OTIS, a citizen of the United States, residing at Chicago, in the county of Cook and State of Illinois, have invented certain new and useful Improvements in Car-Trucks, of which the following is a specification.

This invention relates to that class of car-trucks which are adapted to be used in connection with railroad-cars, particularly freight-cars, and especially to the construction and arrangement of the parts by which the lurching of the car and the endwise movement of the bolster may be permitted without racking or destruction of the same or any part thereof, all of which will more fully hereinafter appear.

The principal object of the invention is to provide a simple, economical, and efficient car-truck.

A further object of the invention is to provide a car-truck with a movable bolster and swinging spring-seats, by which the lurching movement of the car may be permitted without destruction of any of the parts.

Further objects of the invention will appear from an examination of the drawings and the following description and claims.

The invention consists principally in a car-truck in which there are combined bolster-columns, a bolster movably mounted between the same, a spring-seat pivotally mounted in and under each end of the bolster and bolster-columns, and spring mechanism interposed between such spring-seats and the bolster.

The invention consists, further, in the combination of bolster-columns, a bolster movably mounted between the same, a lower spring-seat provided with upwardly-extending lateral arms pivotally mounted in and between each pair of bolster-columns and between the same, an upper spring-seat having a movable bearing on each lower end of the bolster, and spring mechanism interposed between both of such spring-seats.

The invention consists, further and finally, in the features, combinations, and details of construction hereinafter described and claimed.

In the accompanying drawings, Figure 1 is a side elevation of a car-truck constructed in accordance with these improvements; Fig. 2, an enlarged sectional elevation of one end of the bolster and the other parts, taken on line 2 of Fig. 1 looking in the direction of the arrow; Fig. 3, an enlarged sectional elevation of a portion of the mechanism, taken on line 3 of Fig. 1 looking in the direction of the arrow; and Fig. 4, an elevation shown partly in section, taken on line 4 of Fig. 3.

In the art to which this invention relates it is well known that when a car, particularly a refrigerator-car, is taking a curve, where the outside track is at a higher elevation than the inner track, there is such a stress placed upon the mechanisms and parts thereof that it is liable to rack or destroy some of the parts, particularly the flanges of the car-wheels. This invention is intended primarily to provide a simple, economical, and efficient car-truck which will permit of limited movements of certain parts, such as the bolster and spring-supporting mechanism, and tend to permit of the car taking curves without destroying or in any way affecting the efficiency of the parts, as well as relieving the ordinary car-wheel flanges from the tremendous strain usually accompanying the taking of a curve.

In illustrating and describing these improvements I have only illustrated and described that which I consider to be new, taken in connection with so much as is old as will properly disclose the invention to others and enable those skilled in the art to practice the same, leaving out of consideration other and well-known mechanisms, which if illustrated and described herein would only tend to confusion, prolixity, and ambiguity.

In constructing a car-truck in accordance with these improvements—one which is provided with the usual supporting car-wheels *a* and journal-boxes *b*—I make a pair of bolster-columns *c* for each side thereof, the upper ends of which are perforated, as at *d*, both horizontally and at an incline, so that the upper flat arch-bar *e* may be passed therethrough and rest therein. The upper ends of each of these bolster-columns have outwardly-projecting lugs *f*, provided with

dowel-pins *g*, arranged to enter perforations in the upper arch-bar to position the same. To secure these bolster-columns to the lower arch-bars and omit the usual long tie-bolts, 5 such bolster-columns are recessed at an inclination on the inner side, as at *h*, and perforated at the lower part thereof, so that securing-bolts *i* may be passed therethrough and through the lower arch-bars *j*.

10 To support the car-body, I provide a truck-bolster *k* of any suitable construction, one having the usual center bearings *l* and end bearings *m* and which is movably mounted between each pair of bolster-columns. To 15 sustain each end of the bolster in a yielding manner and at the same time permit of its having limited endwise movements, a main spring-seat *p* is provided having upwardly-extending arms *q* at each lateral side thereof, 20 which arms are provided with trunnions *r*, adapted to enter perforations *s* in each of the bolster-columns. Contacting a convex boss *t* on the lower surface of each end of the bolster is a second spring-seat *u*, provided with 25 a concaved recess engaging such convex boss. Arranged between both of these spring-seats is a set of helical coil-springs *v*, which acts to support the upper spring-seat, and thereby each end of the bolster, in a yielding manner. 30 The upper spring-seat above described is provided with flanges *w*, forming a channel which spans the arms of the swinging spring-seat in such a manner that the upper spring-seat moves or swings necessarily with the 35 lower one.

An examination of Fig. 3 of the drawings will show that the lateral swinging arms of the lower spring-seats are arranged to one side of the center or the trunnion or pivotal 40 point. This arrangement is made for the purpose of permitting the spring-seat or the larger part thereof to make a downward swinging movement when the car or that side of the car is on the raised track and taking a 45 curve. When the car is in such position, it will be known that the bolster is moved endwise toward the high part and that if the parts are arranged along a common center line the outer end or major portion of the 50 swinging seat would rise outwardly and upwardly. The present arrangement provides a construction in which the major portion of the spring-seat goes downwardly when that side of the truck is being raised, and therefore assists in compensating for the raising 55 of the trucks—that is, the entire raising movement of the truck is not transmitted to the body of the car.

The arrangement and construction of the 60 bolster-columns described in these improvements are such that they permit of the opposite bolster-columns on each side of the truck being connected together by a pressed-steel tie-bar *y*, of any convenient shape, and secured thereto by means of bolts and nuts *z*. The arrangement shown in Fig. 1 is at a point 65 intermediate the arch-bars; but the construc-

tion is such as to permit this tying across of the bolster-columns at any desired point or points. The arrangement shown in Fig. 1 is 70 particularly convenient in that it permits of the brake-beam mechanism being attached thereto in an economical and efficient manner.

I claim—

1. In a car-truck of the class described, the 75 combination of bolster-columns, a bolster movably mounted between the same, and a swinging seat pivotally mounted in and between such bolster-columns under each end of the bolster at points off center to the center of stress between the bolster and swinging seat, substantially as described.

2. In a car-truck of the class described, the 80 combination of bolster-columns, a bolster movably mounted between the same, a lower spring-seat provided with upwardly-extending lateral arms pivotally mounted in and between each pair of bolster-columns under each end of the bolster, an upper spring-seat 85 above each of the lower seats having a movable bearing on each end of the bolster, and spring mechanism interposed between both of such spring-seats, substantially as described.

3. In a car-truck of the class described, the 90 combination of pairs of bolster-columns, a bolster movably mounted between the same, a swinging spring-seat provided with upwardly-extending arms at each lateral side and off center from the points where they are 95 pivotally secured to the inner sides of each pair of the bolster-columns and between the same, and spring mechanism interposed between such spring-seat and the bolster, substantially as described. 100

4. In a car-truck of the class described, the 105 combination of pairs of bolster-columns, a movable bolster having its ends mounted between each pair of bolster-columns, a spring-seat provided with upwardly-extending arms 110 arranged between each pair of bolster-columns having trunnions pivotally engaged with such bolster-columns, a second spring-seat having a rocker-joint connection between it and the lower surface of each end of the 115 bolster-column, and spring mechanism interposed between each pair of such spring-seats, substantially as described.

5. In a car-truck of the class described, the 120 combination of pairs of bolster-columns, a 120 movable bolster having its ends arranged between each pair of bolster-columns, a main swinging spring-seat provided with upwardly-extending arms arranged between each pair of bolster-columns provided with trunnions 125 pivotally connected with the inner sides of such bolster-columns, a second spring-seat arranged above the first-named spring-seat and having a ball-joint connection with each lower end of the bolster and provided with flanges 130 spanning the arms on the first-named spring-seat, and spring mechanism arranged between such spring-seats, substantially as described.

6. In a car-truck of the class described, the

- combination of pairs of bolster-columns, a movable bolster having its ends arranged between each pair of bolster-columns, a main swinging spring-seat provided with upwardly-extending arms arranged between each pair of bolster-columns and provided with trunnions pivotally connected with the inner sides of such bolster-columns, a second spring-seat arranged above the first-named spring-seats and having a ball-joint connection with each lower end of the bolster and provided with flanges spanning the arms on the first-named spring-seat, spring mechanism arranged between such spring-seats, and tie-rods connecting the bolster-columns on opposite sides of the trucks in pairs and at points intermediate the arch-bars, substantially as described.
7. In a car-truck of the class described, the combination of a pair of bolster-columns at each side thereof provided with transverse perforations at their upper end and outwardly-extending lugs provided with dowel-pins, an arch-bar passed through such perforations resting on the lugs and provided with perforations engaging the dowel-pins, an inclined recess and perforation on the inner and lower side of each of the bolster-columns, bolt mechanism passed through such lower perforations, lower arch-bars through which the bolt mechanism is also passed secured to the lower ends of the bolster-columns, and tie-bars connecting the bolster-columns on opposite sides of the truck in pairs and on the outside thereof and at points intermediate the upper and lower arch-bars, substantially as described.
8. In a car-truck of the class described, the combination of a pair of bolster-columns at each side thereof provided with transverse perforations at their upper end and outwardly-extending lugs provided with dowel-pins, an arch-bar passed through such perforations resting on the lugs and provided with perforations engaging the dowel-pins, an inclined recess and perforation on the inner and lower side of each of the bolster-columns, bolt mechanism passed through such lower perforations, lower arch-bars through which the bolt mechanism is also passed secured to the lower ends of the bolster-columns, substantially as described.
